United States Patent Office

Des. 208,907

Patented Oct. 17, 1967

208,907

PETRI DISH

Kenneth Dale Collister, Charles Henry Patteson, and Robert Mallen Thorsen, Chicago, Ill., assignors to Miles Laboratories, Inc., Elkhart, Ind., a corporation of Indiana

Filed June 8, 1966, Ser. No. 2,607

Term of patent 14 years

(Cl. D16—1)

FIGURE 1.

FIGURE 2.

FIGURE 1 is a perspective view of a petri dish with its cover in place embodying our new design.

FIGURE 2 is a cross-sectional view thereof taken on line 2—2 of FIGURE 1.

We claim:

The ornamental design for a petri dish, substantially as shown and described.
